UNITED STATES PATENT OFFICE.

WILLIAM C. NORCROSS, OF TERRE HAUTE, INDIANA, ASSIGNOR TO AMERICAN MOLD-
ING MACHINE COMPANY, OF TERRE HAUTE, INDIANA, A CORPORATION OF IN-
DIANA.

PATTERN PLATE WITH DRAWING ATTACHMENT.

Application filed December 2, 1921. Serial No. 519,419.

To all whom it may concern:

Be it known that I, WILLIAM C. NORCROSS, a citizen of the United States, residing at Terre Haute, in the county of Vigo and State of Indiana, have invented certain new and useful Improvements in Pattern Plates with Drawing Attachments, of which the following is a specification.

This invention relates to a pattern plate 10 provided with a drawing attachment for the purpose of drawing the pattern from a mold.

It has heretofore been proposed to provide pattern drawing machines which are applied to a molding flask, an instance of which 15 is my Patent No. 1,378,186 dated May 17, 1921, but my present invention is distinguished by embodying drawing means or a drawing attachment self-contained with, and bodily carried by, a pattern plate so that the 20 same plate which carries the pattern, is provided with its own means whereby it may be drawn.

The objects of the invention are, first, the provision of a drawing attachment or 25 means self-contained with a pattern plate; second, to provide novel drawing means carried by the pattern plate adapted for connection to the flask, whereby parallelism will be maintained between the adjoining surfaces of the flask and pattern plate during 30 the drawing operation, thus preventing any tipping or tilting of the pattern plate which would tend to distort the mold, and insuring a perfect "draw."

35 My invention comprises, first, a drawing attachment self-contained with the pattern plate of a mold; second, guide posts having racks, and connected gears or pinions meshing with the racks, the guide posts being adapted for attachment to the flask, whereby the rotation of the gears insures an equal extent of movement of all parts of the pattern plate in relation to the flask, and hence, parallelism as between the flask and 40 pattern plate during the drawing operation; third, improved connections between the guide posts and the flask by which a rigid, self-adjusting connection is obtained and the guide posts are disposed in precise perpendicular relationship to the top of the flask; fourth, in the combination of the means and 45 devices entering into my invention; fifth, in

the provision of other features and relationships of parts appearing more fully herein-after.

55 The disclosure in the accompanying drawings, and which is hereinafter described, represents a practical embodiment of my invention, but, as modifications may be resorted to without departing from the essential principle thereof, such disclosure and description are to be considered as illustrative, instead of restrictive, of the invention.

60 In the accompanying drawings:

Figure 1 is a front elevation showing the 65 flask, and pattern plate provided with my invention, in position on a jolting or jolt-ramming machine, the flask appearing in dotted lines.

Fig. 2 is an end elevation thereof.

70 Fig. 3 is a front elevation, the flask appearing in full lines and the pattern plate and pattern being raised showing how the pattern is drawn, the flask and pattern plate having been first rocked over or inverted.

Fig. 4 is an end elevation of Fig. 3; and

75 Fig. 5 is an end elevation of a modification wherein four guide posts and four gears are used.

The pattern plate appears at 1, the pattern 80 at 2, the flask is shown at 3 and a jolt molding or jolt-ramming machine is shown conventionally at 4.

I wish it to be understood that it is not necessary to employ a jolt-ramming machine 85 as the ramming of the mold may be carried out in any desired fashion. The mold may be rammed by hand, or a jolting machine, or by any other method. To illustrate the steps which are taken in using my invention 90 in a practical manner, I have conventionally illustrated a jolt-ramming machine.

The pattern plate carries guide posts 5 which are provided with rack faces 6 and are slidable through hubs 7 projecting from 95 the pattern plate. The guide posts 5 are transversely slotted as at 8 to receive transversely arranged rockers 9 which have arc-shaped lower edges and oppositely extending parts projecting beyond the sides of the 100 posts 5 and received in cut out portions 10 in the plate 1. The rockers 9 are loosely pivoted on pins 11 tightly secured to the posts 5. Consequently the rockers can rock

or tilt and they thus provide a self-adjusting connection between the posts 5 and the top of flask 3 which prevents cramping of the guide posts in the event that the joint 5 of the flask is not true.

The ends of the posts 5 are tapered and project beyond the plate 1 as shown at 12, said ends constituting dowels or tenons which are provided with slots 13 adapted 10 to receive keys or wedges 14 at the proper time so that when the keys or wedges are driven in position after the tenons 12 are passed through the slots in the flange of the flask 3, the posts 5 are rigidly connected to 15 the flask. When thus connected, the self-adjusting rockers 9 insure that the posts 5 are absolutely perpendicular to the upper face of the flask.

Journalized in suitable bearings 15 at the 20 ends of a web or apron 16 on the pattern plate 1, is a shaft 17 to which is secured two pinions 18 meshing with the respective racks 6 of the guide posts 5. Thus, the pinions 18 are rigidly coupled together so that as 25 the pattern plate 1 is lifted during the drawing operation, (Fig. 3) the pinions 18, hubs 7, and guide posts 5 will insure the maintenance of parallelism between the adjoining faces of the pattern plate 1 and 30 flask 3. This action prevents any tilting or dipping of the pattern plate 1 and hence the pattern cannot possibly distort the mold 3^a, Fig. 3, which has been formed and, as a result, a substantially perfect "draw" will be 35 effected.

The ends of the pattern plate 1 are provided with suitably formed flanges 19 having holes or sockets 20, 21, to receive removable trunnions 22. The sockets or openings 40 20 are located at points corresponding to substantially the center of gravity of the flask, pattern plate and mold combined together. The sockets or openings 21 are located to correspond to substantially the center of gravity of the pattern plate alone. 45

In Fig. 1 the trunnions 22 are shown inserted in the sockets or openings 20 so that the flask and pattern plate can be elevated by any suitable means connected to said trunnions without danger of accidentally overturning. After the flask and pattern plate have been rolled over and the mold set down as shown in Fig. 3, the trunnions 22 are removed and inserted in the sockets or openings 55 21 for the purpose of attachment to said trunnions of any suitable drawing means so that the pattern may be drawn from the mold as shown in Fig. 3.

In Figure 5 I have illustrated the use of 60 two guide posts 5^a at each end of the pattern plate so that four guide posts are employed, instead of two as in the preceding figures. Two shafts 17^a, instead of one shaft, are provided and each of the shafts 17^a carries two pinions 18^a (of which only two are

shown in Fig. 5), the pinions on one shaft meshing with the racks 6^a of one set of guide posts and the set of pinions on the other shaft meshing with the racks 6^b on the other set of guide posts. At each end of the pattern plate, the pinions 18^a mesh with each other. In certain situations it is desirable to use the arrangement shown in Fig. 5.

To prevent the guide posts from dropping out, they are provided with heads 23. 75

The trunnions on the flask 3 appear at 24.

The flask 3 is first set on the pattern plate 1, the dowel ends or tenons 12 passing through the holes in the flange of the flask as shown in Fig. 1, and the mold is rammed 80 as, for instance, by a jolt machine shown conventionally at 4.

After the mold has been suitably rammed, the ordinary clamps are employed to clamp the flask and pattern plate together. Suitable means is now employed to lift the pattern plate and flask from the ramming machine and to roll them over as a unit. For that purpose, the trunnions 22 are inserted in the openings 20 and the lifting and suspending means is attached to said trunnions. 85

The lifting and suspending means is next manipulated to set the mold down, the flask being underneath, as shown in Fig. 3. The clamps that secure the flask and pattern plate together are now removed. The trunnions 22 are then removed and placed in the sockets 21. 95

The keys or wedges 14 are now driven through the slots 13 to rigidly hold the 100 guide posts 5 in position as shown in Figs. 3 and 4, if said keys have not been previously driven in said slots. It will be understood that the keys 14 may be driven into the slots 13 at any previous time during the 105 operation, even before the ramming of the mold, if considered advisable.

The pattern is now drawn by applying to the trunnions 22 any suitable raising means and using said means to lift the pattern 110 plate and pattern, drawing being thus effected merely by lifting the pattern plate. The lifting movement is arrested when the heads 23 are encountered.

After drawing has been effected in the 115 manner shown in Fig. 3, the keys 14 are knocked out and the pattern plate further elevated by means applied to the trunnions 22 when in the sockets 21, thus disengaging the tenons 12 from the flask. The pattern plate is then rolled back to bring the pattern in uppermost position, as shown in Fig. 1, whereupon the guide posts 5 drop down and the pattern plate is ready to receive another flask. 120

If the pattern plate is provided with only two guide posts and two gear pinions, the gear pinions and racks on the guide posts prevent the pattern plate from tilting endwise. The hubs on the pattern plate, in 125 130

which the guide posts slide, combined with the rigid attachment of the guide posts to the flask, prevent lateral tilting.

The gear pinions and racks insure the maintenance of alinement between the pattern and flask during the drawing operation as the pinions at opposite ends of the pattern plate are of equal size, pitch and pitch diameter.

10 I claim:

1. The combination with a pattern plate for molds, of means carried thereby for connecting said pattern plate to a flask which permits the pattern plate to be shifted toward and away from the flask, and means carried by the pattern plate adapted to automatically maintain the pattern plate and flask in alinement when the pattern plate is shifted to "draw" the pattern.

20 2. The combination with a pattern plate for molds, of guide posts carried thereby on which the pattern plate slides, said posts being adapted to be rigidly secured to a flask, and coupled means movable on said guide posts which cooperate with the guide posts to maintain parallelism between the pattern plate and the top of the flask during the drawing operation.

30 3. A pattern plate for molds which has an attachment self-contained therewith, comprising guide posts on which the pattern plate slides, said posts being adapted to engage the flask, and coupled wheels carried by the pattern plate which engage with the guide posts whereby parallelism is maintained between the pattern plate and the upper face of the flask during the drawing operation.

40 4. A pattern plate for molds which has an attachment self-contained therewith, comprising guide posts having racks on which the pattern plate slides, said posts being adapted to engage the flask, and coupled pinions carried by the pattern plate and meshing with the racks on the guide posts, said pinions, racks, and guide posts insuring parallelism of the pattern plate and upper face of the flask during the drawing operation.

50 5. The combination with a flask and pattern plate, of guide posts for the pattern

plate which have racks, and coupled pinions carried by the pattern plate and meshing with said racks.

6. The combination with a flask, of guide posts detachably connected thereto which are provided with racks, a pattern plate, and coupled pinions carried by the pattern plate which mesh with said racks.

7. The combination with a pattern plate 60 for a mold, of guide posts which are slidably mounted in, and are carried by, said pattern plate, and self-adjusting abutments carried by the guide posts which prevent cramping.

65 8. The combination with a pattern plate for a mold, of guide posts which are slidably mounted in, and are carried by, said pattern plate, and self-adjusting pivoted rocker abutments carried by the guide posts 70 which prevent cramping.

75 9. The combination with a flask having openings, of a pattern plate, guide posts provided with self-adjusting abutments adapted to bear on the flask and having dowels or tenons adapted to pass through the openings, means for securing the dowels or tenons to the flask, and a pattern plate slideable on said guide posts.

80 10. The combination with a flask having openings, of a pattern plate, guide posts provided with self-adjusting abutments adapted to bear on the flask and having dowels or tenons adapted to pass through the openings, means for securing the dowels 85 or tenons to the flask, a pattern plate slideable on said guide posts, said guide posts being provided with racks and bodily carried by the pattern plate, and coupled pinions carried by the pattern plate which mesh with racks on the guide posts.

85 11. A pattern plate for molds which is provided with shiftable trunnions.

90 12. A pattern plate for molds having removable trunnions adapted to be affixed to the pattern plate at different points.

95 13. A pattern plate for molds which is provided with a plurality of sockets, and removable trunnions adapted to be inserted in different ones of said sockets.

100 In testimony whereof I affix my signature.

WILLIAM C. NORCROSS.
